UNITED STATES PATENT OFFICE.

JOHN JANUCHOWSKY, OF ST. LOUIS, MISSOURI.

BOTTLE-CAP.

1,257,710.

Specification of Letters Patent. Patented Feb. 26, 1918.

Application filed February 18, 1915, Serial No. 9,042. Renewed November 19, 1917. Serial No. 202,888.

To all whom it may concern:

Be it known that I, JOHN JANUCHOWSKY, a citizen of the United States, residing at St. Louis, in the State of Missouri, have invented certain new and useful Improvements in Bottle-Caps, of which the following is a specification.

My present invention pertains to an improved bottle cap, the same being designed 10 more especially for use in connection with milk bottles such as are now generally employed by the trade in the distribution of milk, cream, buttermilk and the like in small quantities.

15 The object of the invention is to produce a simple and efficient cap or closure which may be readily applied and as readily removed, the cap being so constructed that it will adapt itself to bottles varying in size 20 (within a limited extent) while at the same time it is cheap to produce.

The cap is illustrated in the annexed drawings, wherein:

Figure 1 is a transverse sectional view of 25 the cap;

Fig. 2 a similar view showing it applied to an ordinary or usual milk bottle; and

Fig. 3 a perspective view, partly broken away.

30 The cap is composed of two members or disk like sheets, one of relatively light sheet metal, and an underlay or liner formed from paper and designated as a whole by 2.

The two members are simultaneously 35 formed up in suitable dies and the paper member is closely nested within the metal section. The metal section may be said to comprise a top 3 having a depending and outwardly flaring skirt or collar from the 40 lower edge of which there extends outwardly a rim or flange 5, said rim lying in a plane which is substantially parallel with the plane of the top 3.

In the formation of the cap the rim 5 is 45 crimped or fluted and such flutings extend up into the skirt or collar 4 to a slight extent. The paper underlay or liner partakes of the same form, and the crimping of the paper, simultaneously with the crimping of the 50 metal causes the liner to closely and firmly adhere to or hug the metal section of the closure.

The flaring of the skirt or collar 4 renders the cap universal, that is to say it will fit 55 bottles of different sizes within a quarter of an inch variation in the diameter of the head

or mouth. It is secured in place by being forced or drawn down over the bottle mouth and in the act of such drawing the skirt is drawn inwardly causing the same to hug 60 the bottle, as shown in Fig. 2.

The flange or rim 5 still extends outwardly and affords a projection against which any suitable article or device may be applied to exert pressure to remove the cap. 65 Said rim also tends to stiffen the structure and to prevent accidental deformation thereof.

The metal employed being quite light and ductile may be impressed as at 6 with any 70 desired legend or name during the process of the formation of the cap, such impression being carried into the paper underlay as well as in the metal, in addition to the crimping above mentioned, thereby serving to inter- 75 lock the metal and paper together.

While the cap is designed for general application it is especially useful in connection with milk bottles, sealing the same sufficiently tight to permit the contents of the 80 bottle or container to be pasteurized, a practice which is carried out to a very great extent at the present time.

Having thus described my invention, what I claim is:—

1. A sealing device, consisting of the combination of a bottle having an outer annular plain face adjacent its upper end or mouth; a cap comprising an outer cup-shaped member formed from thin malleable metal, said member having a top, a downwardly-extending and outwardly-flaring skirt, and an outwardly-extending crimped flange, the crimping extending into the lower portion of said skirt; and a paper liner closely fitting the under face of said cup-shaped member and having crimped portions conforming to the crimping of the metallic member, the skirt hugging the outer plain face of the bottle mouth and serving when the cap is forced 100 downwardly into sealing contact with the bottle to hold the cap in place.

2. A sealing device, consisting of the combination of a bottle having an outer annular plain face adjacent its upper end or mouth; a cap comprising an outer cup-shaped member formed from thin malleable metal, said member having a top, a downwardly-extending and outwardly-flaring skirt, and an outwardly extending crimped 105 flange, the crimping extending into the lower portion of said skirt; and a paper

liner closely fitting the under face of the top and the outwardly-flaring skirt and having crimped portions conforming to the crimping of the skirt, the skirt and liner hugging 5 the outer plain face of the bottle-mouth and serving, when the cap is forced downwardly and drawn into sealing contact with the bottle, to hold the cap in place.

3. A sealing device, consisting of the combination of a bottle having an outer annular plain face adjacent its upper end or mouth; a cap comprising an outer cup-shaped member formed from thin malleable metal, said member having a top, a downwardly-extending and outwardly-flaring 10 15

skirt, and an outwardly-extending crimped flange; and a paper liner closely fitting the under face of said cup-shaped member and the skirt said skirt and liner hugging the outer plain face of the bottle-mouth and serving, when the cap is forced downwardly and drawn into sealing contact with the bottle, to hold the cap in place. 20 25

In testimony whereof I have signed my name to this specification in the presence of two subscribing witnesses.

JOHN JANUCHOWSKY.
